UNITED STATES PATENT OFFICE

ARLE M. SALTNAAS, OF MINNEAPOLIS, MINNESOTA

DRAFTING INSTRUMENT

Application filed February 13, 1931. Serial No. 515,623.

This invention relates to an improved drafting tool or instrument which is provided with a receptacle.

In carrying the inventive conception into practice, I have found it expedient and practical to provide a duplex structure which is characterized by a novel pen holder and grip, the parts being so placed together as to form a receptacle.

More specifically speaking, the improved structure embodies a tubular pen holder which has the additional function of a receptacle and the handle being frictionally and telescopically fitted in a removable way into the adjacent end of the holder.

The entire assembly is shown plainly in Figure 2 and the other views are employed to illustrate the details.

In the drawings:

Figure 1 is a side elevational view of the improved instrument.

Figure 2 is a view in section and elevation showing the general assembly.

Figure 3 is an elevational view of the type of handle provided with a metal eradicator or eraser.

Figure 4 is a view like Figure 3 showing the detachable and adjustable rubber ink eraser.

Figure 5 is a perspective view of the pen holder per se.

Figure 6 is a cross section on the line 6-6 of Figure 2.

Figure 7 is a cross section on the line 7-7 of Figure 3.

Figure 8 is a perspective view showing the ferrule and reduced end portion of the handle.

Figure 9 is a perspective view of the metal scraping or erasing blade.

As shown in Figure 5, the pen holder which of longitudinal elongated form and of conventional configuration, is denoted by the numeral 10. It comprises a rubber casing 11 and a metal lining tube 12. In one end is a plug 13 as seen in Figure 2 to accommodate and hold in place the conventional pen 14.

The opposite ends of the lining sleeve 12 are formed with flanges to retain the rubber grip 11. The handle 15 is of conventional

configuration and has one end reduced in diameter as indicated at 16 to accommodate a metal projecting ferrule 17. The ferrule is of cylindrical cross sectional shape and formed intermediate its ends with a shoulder or stop bead 18.

Moreover, the handle 15 is somewhat tapered to facilitate insertion into the adjacent end portion of the pen holder. The plug 13 fitting into this pen holder converts the same into a seat as well as a receptacle to accommodate the telescopically fitting handle.

As before indicated, there are two forms of erasers, namely, the rubber type and the metal scraping blade type. The metal blade is indicated in the drawings by the numeral 20 and as seen in Figure 9 includes an anchoring tang or shank 21 which is fitted into the ferrule covered portion of the handle 15. In Figure 4, the ferrule is provided with a threaded or screw-end coupling 22 to accommodate a rubber ink eraser 23.

Thus, the device as seen in Figures 3 and 4 may be employed in an optional or interchangeable manner.

In both forms of the invention I provide the metal lined, rubber covered pen holder which has the additional function of forming a socket or receptacle as well as a protecting sheath to protect the eraser equipped end portion of the handle. Metal to metal contact between the ferrule on the handle and the lining in the holder provides a frictional coupling connection between the two parts of the tool so as to maintain them in proper associated relationship for convenient usage.

The novelty is predicated upon the simplicity and economy of arrangement of parts as well as the extended degree of usage. Consequently, the device is of a more diversified character and yet has the external appearances of an ordinary ink pen, such as is used most satisfactorily by draftsmen.

It is thought that the description taken in connection with the drawings will enable a clear understanding of the invention to be had. Therefore, a more lengthy description is thought unnecessary.

While the preferred embodiment of the

invention has been shown and described, it is to be understood that minor changes coming within the field of invention claimed may be resorted to if desired.

5 I claim:

A new article of manufacture, comprising a handle, a metal ferrule fitted on one end of the handle and having a bead thereon forming a shoulder, a sleeve having an outwardly extending flange at each end thereof with one end of the sleeve fitting over the ferrule with a flange on the sleeve abutting the shoulder bead to limit the entrance of the ferrule in the sleeve, a plug closing 10 the other end of the sleeve and forming with the ferrule a receptacle in the sleeve and a resilient sleeve carried by the first mentioned sleeve and retained thereon by the two flanges.

15 In testimony whereof I affix my signature.

20 ARLE M. SALTNASS.
